United States Patent Office.

HENRY WHITALL, OF WOODBURY, NEW JERSEY

Letters Patent No. 64,817, dated May 14, 1867.

IMPROVEMENT IN MACHINES FOR GRINDING THE CUTTERS OF HARVESTERS.

The Schedule referred to in these Letters Patent and making part of the same.

TO ALL WHOM IT MAY CONCERN.

Be it known that I, HENRY WHITALL, of Woodbury, New Jersey, have invented an improved Machine for Grinding the Cutters of Harvesters; and I do hereby declare that the following is a full and exact description thereof.

The object of my invention is to provide a small, cheap, portable machine for grinding the cutters of harvesters and mowing machines, which may be easily carried by hand into the field by the operator of the mowing and reaping machine, and which may be readily applied to the same to grind the cutters without taking them out of the machine.

The only means now in use for sharpening such cutters is the common grindstone. When they become dull the cutter-bar must be disconnected from the connecting-rod of the machine and be withdrawn from its position therein, or, as is done in some cases, the cutters are detached from the bars by removing their screws. They are then carried from the field to the house, or where the grindstone is to be found, upon which they are ground in the ordinary manner of grinding tools by hand, which commonly requires the labor of two persons, one to hold them on, the other to turn the stone, a very tiresome, tedious, and time-losing practice. It is also quite difficult to grind them truly in this manner, as few such grindstones are provided with rests or gauges to determine the proper relative inclination of the bevelled edge of the cutter to the face of the stone, without which it is extremely difficult to do the work well. In consequence of these difficulties in the way of properly and readily sharpening the cutters they are generally allowed to run until they get very dull, causing much greater labor for the horses, and doing the work in a much less satisfactory manner.

Now, my invention is intended to overcome these difficulties, and is arranged so it may be applied to any machine, at any time when the cutters have become dull, (or when it is desirable to let the horses stop a short time for rest,) in such a manner that the edges of the cutter may be ground uniformly upon the same angle without any material variation, and requiring only one person to do it without loss of time in removing the cutters from the machine.

The principal features of my invention are—

First. Arranging the stone or vulcanite wheel upon a sliding frame that shall be made to traverse back and forth from front to rear of the cutters in line with and at the same time that the periphery of the stone is made to revolve against the cutting edge.

Second. Arranging the mandrel of the stone upon the said sliding frame at such an angle that when in working position it shall be in a vertical plane parallel with the cutter-bar.

Third. Arranging the support of the said sliding frame upon an axis upon which it may oscillate so as to present the stone to either edge of the cutter, and providing for adjusting the same so that the face of the stone shall be parallel with the bevelled edge of the cutter.

Fourth. Arranging the horizontal support of the oscillating frame upon its vertical supports in such a manner that the sliding frame may be adjusted so as to move in a line parallel with either edge of the cutter, and also in a horizontal plane parallel with the surface of the cutter.

Fifth. The arrangement of a clamp whereby the grinding machine is readily clamped securely to the ground and to the harvester or mowing machine when the cutters are to be ground.

Having thus generally described the nature and object of my invention, I will now proceed to describe more particularly the construction and operation of the same reference being had to the accompanying drawing, in which—

Figure 1 represents a perspective view of my machine in position to grind the cutters on one edge with the cutter-bar in the harvester ready for use.

Figure 2 is a perspective view of the clamp.

Figure 3 is a sectional view of one of the sleeves C, showing the annular groove k.

Figure 4 is a section of one of the sleeves and posts, showing the screw f and nut i.

A and A' are base-plates to which the hollow slotted posts B and B' are secured. C and C' are sleeves made to slide vertically on the said posts by means of screws f and nuts i. The nuts project through slots in the posts and into annular grooves k in the sleeves C, or in place of the screws f and nuts i the sleeves may

be adjusted by hand and secured by set-screws l l' . Each sleeve has a projection extending horizontally from one side. D is a bent support or frame jointed at each end to one of the sleeves by means of said projections. E is an oscillating frame pivoted by screws a and a' to the support D. F is a sliding frame to which the shafts g and h are secured by journal boxes b and b' and c and c' . I is a long screw secured at both ends to the oscillating frame E. j is a worm on shaft g , which communicates motion to a worm-wheel (not seen) which revolves in and is secured to nut J on sliding frame F. The said worm-wheel has a screw hole through its centre, through which the screw I passes. G and H are gears to communicate motion to shaft h . M is the stone or vulcanite-wheel arranged upon the sliding frame at such an angle as will cause the sides of the stone to stand in a line at right angles with the cutter-bar of the mowing machine. L is a plate projecting downward from the front end of the main support D, having a curved slot, m . K is a set-screw passing through the slot m , and screwing into a boss upon the cross-bar of the oscillating frame E. e₁ e₂ e₃ and e represent the fingers of a mowing machine. d₁ d₂ d and d represent the cutters of the same. P represents a clamp, of which p is a lever having a chain, q, attached to its short arm, and another chain, s, attached to its long arm, and a fulcrum supported in the grooves in the stock of the clamp adjacent to the mortise.

The operation is as follows: The cutter-bar having been adjusted so that each one of the edges of all the cutters upon the same side is presented about midway of the spaces between the fingers, the base-plate A is then placed upon the ground in front of the cutter-bar and parallel with it. The base-plate A' is placed in a similar manner upon the machine directly in rear of the cutters. They are then adjusted so that the oscillating frame will stand in a line parallel with the edge of the cutter which is to be ground. The clamp P is then placed with one foot upon base-plate A, and the other on plate A' in such a position that the hook q may be secured to one of the fingers when the long arm of the lever is drawn down by the chain s, and secured to a pin in the beam of the said clamp with sufficient force to secure the base-plates A and A' firmly in their places. The oscillating frame E is then adjusted upon its axis so that the face of the stone on the under side is parallel with the bevelled edge of the cutter. The said frame is secured in this position by tightening up set-screw k. The sleeves C and C' are then adjusted by the screws f or the set-screw l, so that the sliding frame and oscillating frame are brought to a position parallel with the surface of the cutter, and at the same time the stone is made to bear on the cutter with sufficient force to perform the grinding of the same, when the operator, by applying motion to the crank on shaft g will cause the stone M to rotate and move in one direction until it has reached one end of the cutter's edge, then by turning the crank in the opposite direction the stone will also traverse in an opposite direction, this operation being repeated until the cutter is sufficiently sharpened. The clamp is then released, and the machine adjusted to the corresponding edge of the next cutter, and the same operation is repeated until all the cutters are sharpened upon one edge. The cutter-bar is then adjusted so that the opposite edges of the cutters are in the proper position between the fingers, and the base-plates A and A' are placed so as to adjust the sides of the oscillating frame in a line parallel with the edges opposite to those already ground, when, the set-screw K being loosened, the oscillating frame E is turned a half revolution on its axis, which will bring the grindstone in the same position relatively to the unground edges of the cutters. The operation is then proceeded with in the same manner as above described. In consequence of the faces of the stone being presented to the cutters at right angles to the cutter-bar, the stone will work closely into the angle between the cutters where they come together.

Having thus fully described my invention, what I claim and desire to secure by Letters Patent, is—

1. A portable machine adapted to grind the cutters of mowing and reaping machines, when arranged and operating substantially in the manner described.

2. In combination with a machine constructed substantially as described, I claim the clamp P when arranged for joint action with the said machine as and for the purpose described.

In testimony whereof I do hereby subscribe my name this twentieth day of February, one thousand eight hundred and sixty-seven.

HENRY WHITALL.
